GLASS LINED HOT WATER TANK

Otto E. Uecker, Milwaukee, Wis., assignor to A. O.
Smith Corporation, Milwaukee, Wis., a corpora-
tion of New York

Application May 6, 1940, Serial No. 333,628

3 Claims. (Cl. 122—17)

This invention relates to enamel lined hot water tanks.

An object of the invention is to provide a vitreous enameled tank which has a central flue and is adapted to the heating of water by means of gas.

These and other objects of the invention will be clear from the following detailed description and the accompanying drawing in which:

Figure 1 is a section through a tank embodying the invention;

Fig. 2 is a section through a modified construction; and

Fig. 3 is a section illustrating another modification of the invention.

Referring to the drawing, and at first to Fig. 1, the tank comprises a shell 1, a lower head 2, a central flue 3, and an upper head 4. Suitable openings 5 are provided for attachment to pipes for conducting water to and from the tank, for the insertion of thermostatic elements, or for other purposes. The openings shown in the drawings are provided with flanges for connection to other fittings, but it is to be understood that the specific form of the openings forms no part of this invention and that other means of connection may be employed.

In fabricating the tank, the shell 1 is formed from steel and slightly expanded at the ends to make flared sections 6 for the reception of the heads. All fittings for openings in the shell that are to be applied before enameling are prepared and joined to the shell. Vitreous enamel frit is then applied to the inner surface of the shell and fused thereon to form an enamel or glass lining 7. As many coats of enamel are applied as are needed.

The lower head 2 is stamped from metal and pierced with a hole around which the metal is turned up to form a short flange 8. A tube 3 for the flue is welded to the flange at 9 by flash, resistance, arc, or other method of welding and any excess weld metal or flash or burr produced in the welding operation is trimmed away to leave a smooth joint. Enamel frit is then applied to the lower head and the attached flue and fused thereon to form a coating 7, which covers the head and the flue 3 up to within a short distance of its end.

The enamel coating is to be applied to those metal surfaces which face the space enclosed by the tank to protect them from the corrosive action of water in the tank, but it is also to be understood that the lower surface of the lower head and the inside of the flue may likewise be enam-

eled to protect them against the action of products of combustion from the heater used to heat the tank.

The upper head 4 is prepared with an upturned flange 14 for the reception of the flue 3 and enameled. It will be seen that all enameled surfaces which are to be exposed to the water in the tank are readily accessible and can be thoroughly inspected for the detection of any defects in the enamel.

The heads are then assembled in position as shown in Fig. 1 and joined to the shell by the deposition of weld metal at 16 and 11. The method of making such welds between the heads and shell is described in full detail in my co-pending application for patent, Serial No. 215,651, filed June 24, 1938, and it is therefore unnecessary to repeat the description here. The flue is joined to the upper head by welding at 12.

To facilitate the welding operation, the upper end of the flue is preferably left unenameled for a distance about equal to its projection above the juncture with the head.

Alternatively, the flue can be made shorter as shown in Fig. 3 so that its end is flush with the juncture with the upper head. Weld metal 13 is then deposited on the bare ends of the flue and the upturned flange 14 to unite the two together. This procedure facilitates the welding operation, but requires a closer control on tolerances to insure that the ends of the flue 3 and flange 14 will be substantially flush when the parts are assembled together.

In the embodiment illustrated in Fig. 2, the upper head 15 is of different shape than the lower head, and is secured by weld 16 to the shell 1 before enameling and excess weld metal is trimmed away to leave a smooth joint. The shell and upper head are then enameled as one unit, the flue and lower head as another. It will be seen that in this case also the enamel surfaces exposed to water in the tank are readily accessible for inspecting prior to assembly since the lower end of the shell is open. After inspection, the two units are assembled and joined together by weld metal deposited at 17 and 18. In this case there are but two welded joints to make after enameling instead of three.

The construction shown in Fig. 3 may be used in the embodiment illustrated in either Fig. 1 or Fig. 2.

The tank is designed for use with a burner placed below the lower head. The hot products of combustion pass up the flue to a chimney and heat the water in the tank.

The invention is claimed as follows:

1. A ceramic enamel lined water heater storage tank constructed of parts assembled after enameling, comprising a cylindrical shell member lined with ceramic enamel, end heads lined with similar enamel, and a cylindrical flue member extending longitudinally in said shell and connecting said end heads, the outer surface of said flue member being coated with ceramic enamel, at least one of said heads and one of said cylindrical members being integral and merged with one another along smooth lines without sharp corners tending to injure the enamel and having their enamel coatings extending continuous and unbroken over the surface thereof exposed to liquid in the tank, and the remaining members being welded together along lines at the outer edges of overlapping lined sections thereof and substantially removed from the body of the tank where injury to the enamel lining by welding is avoided.

2. A ceramic enamel lined water heater storage tank constructed of parts assembled after enameling, comprising a cylindrical shell member lined with ceramic enamel, end heads lined with similar enamel, and a cylindrical flue member extending longitudinally in said shell and connecting said end heads, the outer surface of said flue member being coated with ceramic enamel, the inverted lower end head of the tank and the flue member being integral and merged with one another along smooth lines without sharp corners

tending to injure the enamel and having their enamel coatings extending continuous and unbroken over the surface thereof exposed to liquid in the tank, and the assembly joints being welded along lines at the outer edges of overlapping lined sections of the parts and substantially removed from the body of the tank where injury to the enamel lining by welding is avoided.

3. A ceramic enamel lined water heater storage tank constructed of parts welded together prior to enameling and at least two major parts assembled and welded together after enameling, comprising a cylindrical shell lined with ceramic enamel, end heads lined with similar enamel, and a cylindrical flue extending longitudinally in said shell and connecting said end heads, the outer surface of said flue being coated with ceramic enamel, the weld joints between at least two of said parts being made prior to enameling and being of the butt-weld type providing an integral merger of the parts with one another along smooth lines without sharp corners tending to injure the enamel and said parts having their enamel coatings extending continuously over the weld joint, and the remaining weld joints, made after assembly, being welded along lines at the outer edges of overlapping lined sections of the parts and substantially removed from the body of the tank where injury to the enamel lining by welding is avoided.

OTTO E. UECKER.
